UNITED STATES PATENT OFFICE.

QUINCY G. SHELDON, OF ELBURN, ILLINOIS.

FENCE-MOLD.

SPECIFICATION forming part of Letters Patent No. 783,901, dated February 28, 1905.

Application filed November 17, 1904. Serial No. 233,153.

To all whom it may concern:

Be it known that I, QUINCY G. SHELDON, a citizen of the United States, residing at Elburn, in the county of Kane and State of Illinois, have invented new and useful Improvements in Fence-Molds, of which the following is a specification.

This invention is a portable mold for fence-posts, and embodies a construction which may be used in molding fence-posts at the place where they are to stay.

The invention comprises a mold suitable to be placed over a post-hole, which mold when the post is set can be removed and taken to another place. A construction permitting this operation enables fence-posts to be quickly made and set with least amount of labor, time, and expense.

The invention is illustrated in the accompanying drawings, in which—

Figures 1 and 2 are elevations of the mold. Fig. 3 is a horizontal section.

The mold comprises a cylindrical shell, slightly tapered and formed of flexible metal such, for example, as galvanized iron. The body portion of this cylinder is indicated at 6, and it opens at one side to permit the same to be removed from the post. At said side it has flanges 7, which come together when the mold is closed. At the base of the flange on one side are loops 8, which extend through slots 9, produced in the other flange. These loops receive a locking-rod 10, which holds the joint closed. The cylinder is provided at its lower end with outwardly-projecting legs 11, which rest on the ground when the mold is set over a post-hole, as indicated at Figs. 1 and 2.

The post for the making of which the mold is particularly designed has a wire embedded therein, with projecting loops for holding the line-wires, and in order that such wire may be embedded in the post when it is molded the mold has in its side openings 12, through which loops of wire (indicated at 13) extend. The wire is held in position in the mold by a

locking-rod 14, which is inserted through the loops referred to. The rods 10 and 14 are both of sufficient length to be driven into the ground, so that they assist in holding the mold in a vertical position.

In use the mold is set up over a post-hole, with the wire 13 in place and the legs resting on the ground. Cement is then poured into the top of the mold to fill the post-hole and mold. When the cement is set, the rods 10 and 14 are pulled out and the mold is sprung open far enough to allow it to be slipped off of the post. The wire 13 will remain embedded in the post, with its loops projecting beyond the surface thereof to receive the line-wires.

What I claim as new, and desire to secure by Letters Patent, is

1. A mold, adapted for molding posts in place, open at top and bottom and having outwardly-extending legs at the bottom, adapted to rest on the surface of the ground around the post-hole.

2. A mold comprising an upright openable flexible tubular structure having outwardly-extending supporting-legs at the bottom.

3. An upright post-mold open at top and bottom and openable at the side, and having openings in its side wall to permit the projection of loops of a wire contained in the mold, and a locking-rod on the outside adapted to be inserted through the projecting loops, to hold the same in place.

4. An upright post-mold open at top and bottom and made of flexible material bent to shape and having slot-and-loop connections at its meeting edges and openings in the side permitting the projection of loops of a wire in the mold, and locking-rods extending through said loops.

In testimony whereof I have signed my name to this specification in the presence of two subscribing witnesses.

QUINCY G. SHELDON.
